UNITED STATES PATENT OFFICE

2,489,962

OVEN DOOR

Christopher L. Hardwick, Cleveland, Tenn.

Application November 29, 1946, Serial No. 712,966

2 Claims. (Cl. 126—200)

1

My invention relates to stove doors and more particularly to that type of oven door which is provided with a covered opening or window therein, thus enabling the housewife to note the progress of the baking or roasting at any time desired without opening the door itself.

It has been the custom heretofore to cover the window opening in such doors with at least two spaced panes, the air space between them serving to reduce the escape of heat to a minimum. However, considerable trouble has been experienced due to the fact that the glasses could not be sealed tightly together and consequently, fumes and greasy odors from cooking would collect in the inaccessible space between them and from where they could not be readily cleaned off by the housewife.

One of the principal objects of the present invention is to overcome the foregoing objections by providing adequate seals at both outer and inner faces of the panes.

Other objects and advantages of my invention will be apparent as the description is considered with the accompanying drawings, in which:

Figure 1 is a perspective view of a stove showing my invention installed in the oven door thereof;

Figure 2 is a side elevation showing the door removed from the stove;

Figure 3 is a rear view of the door removed from the stove;

Figure 4 is a front face view of the lining plate and its brace member or plate disassembled from the front plate and showing the manner in which the window glass is attached in place;

Figure 5 is a section on line 5—5 of Figure 4;

Figure 6 is a section on line 6—6 of Figure 4;

Figure 7 is an enlarged fragmentary detail view on the line 7—7 of Figure 4;

Figure 8 is an enlarged fragmentary detail view taken on the line 8—8 of Figure 4, and

Figure 9 is an enlarged fragmentary detailed view of a modified form of window unit showing the use of three spaced panes.

Referring more particularly to the drawings, 1—45 denotes a cooking stove or range comprising a body 2 supported upon a base 3 and provided with top burner openings 4. The body 2 is also provided with side utility compartments 5, a single bottom utility compartment 6 and an oven compartment 7, all of conventional construction. The oven opening is normally closed by a door 8 hinged at its bottom edge in any desirable manner, not shown.

The oven door 8 consists of a front enameled

5 rectangular sheet metal plate 9 and a back lining member or plate 10 also of sheet metal. The front plate 9 is formed with flange 11, projecting inwardly or rearwardly from its side, top and bottom edges and adapted to receive or fit snugly over corresponding flange 12, projecting outwardly or forwardly from the side, top and bottom edges of the lining plate 10. The bottom horizontally disposed portion of inwardly or rearwardly extending flange 11 is formed with an upwardly bent extension 13 which prevents separation of the plates 9 and 10 at their lower ends. The upper end of the lining plate 10 seats against a pair of spacing brackets 14, only one of which 15 is shown, secured to and projecting rearwardly from the upper rear face of the front plate 9. These brackets are provided with apertures 15, which register with corresponding apertures 16 in the lining plate for a purpose presently described. By first inserting the lower end of the lining plate behind the extension 13 the lining plate member 10 can be readily moved into place within the confines of flange 11, and in position to be secured to the front plate 9. This is accomplished by means of headed screws 50, adapted to be inserted forwardly through apertures 16 and thence through apertures 15, in the order named. Any suitable means, not shown, is employed to hinge the lower end edge of the oven door 8 to the stove body 2, and curved arms 20 projecting rearwardly and downwardly from the sides of flange 12, are formed with hook shaped ends 21 adapted to be connected to conventional spring mechanism, not shown, for normally maintaining the door 8 in closed or open position. Both front plate 9 and lining plate 10 are provided with rectangular window openings 17 and 18 respectively.

40 Secured snugly to the lining plate in any suitable manner, as by welding contacting areas, is a brace member or plate 19, conforming in general outline and shape with plate 10, and serving to brace and reinforce the lining member or plate 10. This brace member is formed with a rectangular window opening 22 which, generally speaking, registers with the window openings 17 and 18 just described and the intermediate portion of the brace member is bellied forwardly, as at 35, from the correspondingly rearwardly bent or bellied adjacent portion 36, of the lining plate 10, for a purpose presently described.

45 The window openings previously described are normally closed by a readily assembled and disassembled glass holding unit or member 23 in which spaced front and rear glass members 24

and 25 are respectively supported. The unit 23 comprises front and rear rectangular frame members 26 and 27 and a U-shaped rectangular spacing member 28, of narrow thin sheet metal. The body of the front member 26, along the side, top and bottom portions thereof, is bent forwardly and thence inwardly to respectively provide flanges 29 and 30 against which the edges of the front glass member 24 seat. The body of the member 27 is correspondingly bent rearwardly and thence inwardly to provide flanges 31 and 32 against which the edges of the rear glass member 25 seat. It will be seen that the outwardly extending flanges 33 and 34 of spacing member 28 are snugly received between the inner side edges of the opposing faces of the panes 24 and 25 and also that these flanges 33-34 seat against the flanges 29 and 31. The flat adjacent faces of the body portions of the frame members 26 and 27 seat flush against each other while the rear face of the frame member 27 seats snugly against the bellied portion 35 of brace plate 19. The parts just mentioned are secured together and to the brace plate 19, by screws 37, which pass through aligned openings 38 and 39 in the frame members, and thence through threaded openings 40 formed in the brace member or plate 19, thus securing together the component parts of unit 23, and securely attaching the latter to the lining member or plate 10. When the parts are thus assembled the flanges 33 and 34 of U-shaped spacing member 28 crowd the glass into tight sealing contact with the flanges 30 and 32 while a tight seal will also be effected between the glass holding frame and the brace member 19. This prevents fumes or greasy products from gaining access to the dead air space between the panes.

The unit 23 can be assembled at the factory, and if desired the frame members 26 and 27 may be welded, bolted or crimped together thus making the unit tamper-proof in the field. At the same time this construction permits of ready disassembly for replacing glass when broken without interfering with the desired seal when reassembled. The oven compartment 1 is preferably provided with an electric bulb, not shown, for illuminating the interior of this compartment.

From an inspection of Figure 9 it will be seen that by increasing the depth of either one or both of the outer seal or frame members 26-27, additional sheets of glass and spacers may be inserted, so as to increase the effectiveness of the unit 23. Thus, in Figure 9, I have shown a slightly modified form of the invention wherein frame members 26' and 27' are of increased depth for the accommodation of an additional U-shaped spacing member 28' and an additional glass 50'.

Having thus described my invention, what I claim is:

1. An oven door comprising a front plate and a lining plate therefor, said plates having registering window openings, a brace plate connected to the forward face of said lining plate and formed with a window opening registering with said first mentioned window openings, said brace plate formed with a flat surface extending about the

window openings in said lining plate and said brace plate, a glass supporting unit comprising front and rear frame members having body portions in superposed relation to each other, each of said body portions of said frame members having a flange extending at substantially a right angle thereto and a flange extending parallel with said body portion, spaced panes having their respective edges seated against said angular flanges, a channel member engaging with said angular flanges between said panes and forcing one side edge of each of the panes against one of the said parallel flanges, and means for connecting the body portions of said frame members together and to said flat surface for supporting said panes in alignment with said window openings.

2. An oven door comprising a front plate formed with a rearwardly extending flange and a lining plate having a forwardly projecting flange telescoping within said first mentioned flange, a brace plate superposed upon the front face of the lining plate, registering window openings formed in said front plate, lining plate and brace plate, said brace plate having a forward bellied portion extending about the window openings in said lining plate and said brace plate, a glass supporting unit comprising front and rear superposed frame members supported on said bellied portion of said brace plate, said front frame member having a portion thereof bent forwardly and thence inwardly to form a forwardly extending flange and an inwardly extending flange respectively, said rear frame member having a portion thereof bent rearwardly and thence inwardly to form a rearwardly extending flange and an inwardly extending flange respectively, a front pane and a rear pane respectively seated and sealed at their edges against said forwardly and rearwardly extending flanges on said frame members, and a channel member between said panes for forcing said panes into sealing contact with the respective inwardly extending flanges on said frame members, and means for detachably securing said frame members to each other and to said brace member with said panes in alignment with said window openings.

CHRISTOPHER L. HARDWICK.
